UNITED STATES PATENT OFFICE.

EMIL KOTTUSCH, OF CHICAGO, ILLINOIS, ASSIGNOR TO ARTHUR E. STENZEL, OF CONGRESS PARK, ILLINOIS.

PISTON-RING.

1,172,369.

Specification of Letters Patent.

Patented Feb. 22, 1916.

Application filed June 21, 1915. Serial No. 35,220.

To all whom it may concern:

Be it known that I, EMIL KOTTUSCH, a subject of the Emperor of Germany, residing at 2354 North Clark street, in the city of Chicago, county of Cook, and State of Illinois, have invented certain new and useful Improvements in Piston-Rings, of which the following is a specification.

My invention relates to improvements in piston rings and more particularly to rings of that class which are adapted to be used in internal combustion motors.

The objects of my invention are to so construct the joint portion of the ring that a gas tight joint is secured without interfering with the limited circumferential expansion or contraction of the ring, to make the segmental insert separate and detachable from the remainder of the ring so that it may be replaced if worn, damaged or broken and to form the end edges of the segmental insert and the slots in which it fits so as to extend obliquely. These and other objects I accomplish as set forth in the following specification and as more fully and particularly pointed out in the appended claim, reference being had to the accompanying drawings in which a preferred embodiment of my invention is shown.

In the drawings: Figure 1, is a side elevation of my improved piston ring, the segmental insert being shown in dotted lines. Fig. 2, is an edge view of my improved piston ring in a compressed condition. Fig. 3, is an edge view similar to Fig. 2, with the piston ring in expanded or uncompressed condition. Fig. 4, is an enlarged side view of the segmental insert detached from the ring. Fig. 5, is an edge view of the segmental insert shown in Fig. 4.

In referring to the preferred embodiment of my improved piston ring as shown in the accompanying drawings in detail like numerals designate corresponding parts.

My improvement comprises a ring 1, which is provided with two ends 2, each having a longitudinal slot 3, formed therein, and a segmental insert 4, which is adapted to be permanently fitted and secured in the slot in one end of the ring 1, and to have its opposite end portion slidably project in the slot of the opposite end of the ring.

I prefer to extend the slots 3, centrally, longitudinally in the ends of the ring and

with the side walls thereof in parallel planes with the side surfaces of the ring and to form said slots of even and uniform width throughout. I also prefer to extend the end wall at the inner termination of each slot, obliquely outward or at an angle to the end edge of the ring, that is to extend said end wall diagonally outward and away from said end edge of the ring.

The segmental insert 4, is preferably constructed substantially as shown in Figs. 4 and 5, the top and bottom surfaces being in parallel planes, and the side edges being curved to approximately correspond to the curvature of the ring. The end edges of the insert are cut to extend obliquely and so as to fit against and contact throughout with the oblique end walls of the slots when the ring is compressed.

Preferably I permanently secure one end of the insert in one of the slots 3, by pins or rivets 5, which are fitted through the transverse openings 6, in the insert shown in Fig. 4. The opposite end of the insert projects into the slot in the opposite end of the ring and is free to slide therein as the ring is contracted or expanded in circumference.

If desired the insert may be made of very strong, practically unbreakable tough rigid metal such as steel, while the ring may be formed of a spring metal like cast iron.

The insert is made sufficiently long and the slots sufficiently deep to eliminate any possibility of the ring being expanded or opened far enough to entirely withdraw the free sliding end of the insert from the slot in which it projects.

While I have illustrated and described a preferred form of construction for carrying my invention into effect, this is capable of a wide range of variation, alteration, modification and change without departing from the spirit of my invention, I therefore do not wish to be limited to the construction herein shown and described, but desire to avail myself of all such variations, alterations, modifications and changes as fairly fall within the scope of the appended claim or may be construed to be within the scope thereof by involving the doctrine of equivalents.

What I claim as my invention and desire to secure by Letters Patent is:

A ring of the class described, comprising an annular ring, having longitudinal slots

in the opposed ends thereof, said slots being considerably deeper on the outer surface than the inner surface and being of uniform width throughout and having parallel side walls and oblique end walls, said end walls being substantially straight and diverging from each other outwardly from the inner to the outer surface of the ring, a segmental insert having one end thereof slidably projecting into the slot in one end of the ring and rivets for securing the opposite extremity of the insert in the other slot, said segmental insert having inner and outer curved surfaces corresponding to the curve of the inner and outer surfaces of the ring

and fitting flush with said inner and outer surfaces when the insert is in place in the ring, parallel side surfaces and oblique end edges corresponding to the oblique end walls of the slots and adapted to contact throughout with said oblique end walls when the ring is in compressed condition. 20

In testimony whereof I have hereunto affixed my name in the presence of two witnesses.

EMIL KOTTUSCH.

Witnesses:

JOSEPH JANVIER,
ROBT. KLOTZ.
